UNITED STATES PATENT OFFICE.

WILLIAM H. WINSLOW, OF CHICAGO, ILLINOIS, ASSIGNOR TO WINSLOW SAFETY HIGH-PRESSURE BOILER CO., OF CHICAGO, ILLINOIS, A CORPORATION OF ILLINOIS.

PILOT-BURNER.

1,165,373.

Specification of Letters Patent. Patented Dec. 21, 1915.

Application filed March 18, 1912. Serial No. 684,510.

To all whom it may concern:

Be it known that I, WILLIAM H. WINSLOW, a citizen of the United States, residing at Chicago, in the county of Cook and State 5 of Illinois, have invented a certain new and useful Improvement in Pilot-Burners, of which the following is a full, clear, concise, and exact description, reference being had to the accompanying drawings, forming a 10 part of this specification.

My invention relates to an improved construction of pilot burners for use in connection with small steam boilers and particularly 15 boilers for use in connection with automobiles.

By my invention I separate the main vaporizer from the pilot vaporizer so that the two are subjected to different heating conditions, the pilot vaporizer being subjected to practically constant heat whether 20 the main burner is operating or not, while the main vaporizer is subjected to the heat from the pilot burner and also to a portion of the heat from the main fire. The pilot 25 vaporizer is also made so that it is very readily removable to facilitate replacing it with another if for any reason it gets out of order.

By my invention I also provide that the 30 entire manipulation of the pilot burner may be controlled from a distant point, as for example, from the dash-board of the vehicle when the device is used in connection with an automobile.

35 The several drawings illustrating my invention are as follows:

Figure 1 shows in top view the main burner, the main vaporizer, and the pilot burner assembled in operative relation.

40 This view also shows diagrammatically the arrangement of parts so that the control of the apparatus may be effected from a distant point, as from the dash-board of an automobile. Fig. 2 shows in side view the parts 45 indicated in Fig. 1 with the pilot burner removed. Fig. 3 shows in side elevation and partially in section the pilot burner and vaporizer. Fig. 4 shows in top view the parts shown in Fig. 3, the casing being

50 broken away to better illustrate the relation of the parts. In this figure there is also shown a portion of the main burner to show its relation to the pilot burner. Fig. 5 is a front elevation of the parts shown in Fig. 55 3 to illustrate the arrangement of the in-

terior of the pilot burner and its casing. Fig. 6 shows in front elevation a portion of the mechanism employed for controlling the cock associated with the gas tank. Fig. 7 shows in side elevation mechanism co-operating 60 with the devices shown in Fig. 6 for controlling the cock associated with the gas tank.

Similar numerals refer to similar parts throughout the several views.

As shown in Fig. 1, the main burner 1 is provided with a mixing tube 2 into which the vaporized fuel is projected by the atomizer 3. The atomizer 3 is connected with a pipe 4 which supplies the vaporized 70 fuel to the atomizer 3 from the pipes 5 of the main vaporizer. These pipes 5 are of comparatively small bore and are secured in parallel relation, having their ends fused 75 into headers 6 and 7 which have closed ends. These parts are secured together by fusion by means of the oxy-acetylene flame so that a permanent structure is the result even though the vaporizer be much overheated by the flame under it. The header 6 is connected directly with the pipe 4 and the header 7 is formed in a loop of large diameter and connects with the supply pipe 8 extending from the burner casing to a control 80 valve 9 from which the supply pipe extends 85 to the main fuel tank, not shown.

It will of course be understood that automatic controlling devices may be employed in the main fuel pipe 8 in addition to the manually controlled valve 9. As such devices do not constitute a part of this invention, they are not herein shown or described.

The valve 9 is provided with a long valve rod 10 to which an operating handle 11 is secured. In this way the valve 9 may be controlled from any desired point distant from the vaporizer, as for example, from the dash-board 12 of an automobile. The closed end of the header 7 has secured to it by fusion, a clip 13 projecting over and resting upon the pipe 8 so that it may move 95 freely thereon. The pipes 4 and 8, where they project through the casing 14 of the boiler, are secured to a plate 15 held in place against the boiler casing by screws 16. The plate 15 constitutes the only support for the main vaporizer, as a result of which the vaporizer is suspended under the boiler over the burner 1 so that the vaporizing tubes 5 are directly over the pilot burner 17 which

projects to the left from the boiler casing as indicated. Thus, the parts of the main vaporizer are free to contract and expand for the heat changes which take place in it and the clip 13 provides a ready means so that the tubes 5 may expand a different amount than the pipe 8 without endangering the structure.

The pilot burner 17 is supplied with fuel by a pipe 18, in which there is located a manual control valve 19, the valve rod 20 of which is extended so that it may be operated by a handle 21 mounted in a convenient position readily accessible to the operator, as for example, upon the dash-board 12 of the automobile. Means are provided for supplying to the pilot burner 17 at the start, acetylene gas for heating it sufficiently so that it will vaporize its own fuel in a manner to be described, and the acetylene gas is supplied for this purpose by means of a tube 22 extending from the pilot burner to the dash-board 12, where it communicates through a suitable cock 23 with the acetylene tank 24.

As shown in Figs. 1, 6 and 7, the operating rod 75 of the cock 23 controlling the flow of gas from the tank 24 has secured to it by means of a clamping screw 76 a double lever 77, one arm 78 of which is pivotally connected to one end of a link 79, the other end of which is pivotally connected with a lever 80 pivotally mounted at 81 adjacent to the dash-board 12. The lever 80 is extended below the pivot 81 and pointed at its lower end to engage the teeth of a detent 82 pivotally supported at 83, and held in engagement with the lower end of the lever 80 by means of a spring 84, by which means the lever 80 is retained in any position to which it may be moved, and thus a means is provided for retaining the cock 23 in its open position to any desired extent. The other arm 85 of the double lever 77 is pivotally connected with one end of a twisted link 86, the other end of which is pivotally connected at 87 with one arm of a bell crank lever 88 pivotally mounted at 89, the other end of this bell crank lever being pivotally connected at 90 with one end of an operating rod 91 which extends forward of the car and terminates in a ring 92 to permit ready engagement of the rod 91 by the operator when it is desired to operate the cock 23 to cause the gas to flow through the pipe 22. In this way a mechanical means is provided for controlling the cock 23, either from the dash-board 12 or from the front end of the vehicle. The pipe 22 supplies the head lamps 93 and 94 through cocks 95 and 96, and communication between the pipe 22 and the pilot burner 17 is controlled by a cock 97 in a branch pipe leading from the pipe 22 to the pilot burner 17. Handles 11 and 21 are secured to the valve rods 10 and 20

near the valves 9 and 19, so that said valves may be operated from the front end of the car if desired.

A sparking device is also provided in connection with the pilot burner, which, in a manner to be shown, ignites the acetylene gas, and the wires 25 and 26 for controlling this spark device are connected with the secondary winding 27 of an induction coil, the primary winding 28 of which is connected with a battery 29 and with one terminal of the interrupter device 30, the other terminal 31 of which is connected by wire 32 with the switch 33 mounted upon the dash-board 12. The contact 34 of the switch 33 is connected by wire 35 with the other terminal of the battery 29. A condenser 36 has its terminals connected with the members 30 and 31 of the interrupter device. A second switch 98 is mounted at the front end of the car and is connected by wires 99 and 100 with the wires 35 and 32, respectively, so that the operation of the interrupter device may be controlled from the front end of the car if desired. As a result of the construction described, when it is desired to start the pilot burner the cock 23 is opened, by means either of the rod 91 or the lever 80, thus permitting the acetylene to flow into the pilot burner and at the same time the sparking mechanism is operated by closing either the switch 33 or the switch 98, which serves to operate the interrupter device and ignite the gas in the pilot burner in a manner to be described.

The pilot burner 17 consists of a separate burner structure secured to the main burner 1 by means of screws 47, as indicated in Fig. 4, said screws extending through a flange which serves to support the pilot burner from the main burner. The pilot burner 17 extends for some distance outside of the casing 14 of the boiler and the projecting portion is surrounded by an inclosing wall 48 within which the pilot burner is divided into two portions 49 and 50 so that the heat produced within the casing 48 will be more evenly distributed around the vaporizing tube 51 of the pilot burner. The casing 48 is extended upward a sufficient distance so as to include a sufficient length of the vaporizer tube 51 to properly vaporize the fuel supplied to the pilot burner and the tube 51 is provided near its upper end with two grooves 52 for engaging the sides of a slot 53 formed in the top of the casing 48 to support the vaporizing tube 51 and the regulating needle valve 54 secured to the lower end of the vaporizing tube 51. The controlling needle valve is operated by a handle 55 so that just the right amount of fuel may be projected from the vaporizing tube into the mixing tube 56 of the pilot burner.

As indicated in Fig. 3, the mixing tube 56 projects nearly to the inner end of the pilot burner 17 and is closed at its inner end,

as shown at 57, and the only passages affording escape openings for the air and vaporized fuel from the mixing tube 56 into the burner 17 are the small holes 58 formed in either side of the tube 56. This provides that if for any reason fuel supplied to the mixing tube 56 by the vaporizing pipe 51 is not sufficiently vaporized, the liquid portion of the fuel is collected in the mixing tube, and runs out of the outer end of the tube, as a result of its inclination in the pilot burner, as indicated.

The upper end of the vaporizing pipe 51 is provided with a coupling member 59 which may be readily connected with or disconnected from the fuel supply pipe 18 by means of a suitable union connector, so that in case of difficulty with the vaporizing pipe 51 or its controlling valve 54, the pipe and valve may be readily removed and another inserted. The casing 48 is provided with a small tunnel-like opening 60 through its wall adjoining the boiler casing, and the pilot burner openings are continued through this opening 60 although they are of restricted size at this point, as a result of which, if for any reason the pilot burner is blown out, the more protected portion of the burner flame contained within the casing 48 serves to again light the main portion of the pilot burner by means of the jets extending through the opening 60. Similarly, if for any reason the fire within the casing 48 is extinguished momentarily, the communicating jets through the opening 60 will again be lighted after the extinguishing cause has been removed.

To facilitate the ready inspection of the pilot vaporizer, the front wall 61 of the casing 48 is readily removable by undoing the screws 62, 62, and for this condition the vaporizer pipe 51 and its associated controlling valve 54 may readily be removed from the pilot burner, since the lower end of the vaporizer pipe is contained in a slot 63 which is open at its outer end. The casing 48 is preferably secured to the pilot burner frame by means of the screws 64, 64, as indicated, and the inclined wall over the sections 49 and 50 of the burner is provided with ribs or fins 65 to prevent undue heating of the casing.

In order to light the pilot burner, use may conveniently be made of a burner tube, 66 opening through the lower portion of one of the sides of the casing 48, which burner tube is connected with the pipe 22 connecting with the acetylene generator. Spark terminals 67 and 68 insulated from each other are mounted in the casing 48 in the path of the gas delivered from the burner tube 66, and these spark terminals are connected with the wires 25 and 26.

As a result of the construction shown and described, when it is desired to start the

pilot burner, either the switch 98 or the switch 33 is closed and the cock 23 is opened, either by the rod 91 or the lever 80, as a result of which acetylene gas is introduced into the casing 48 by means of the burner tube 66, and ignited by means of the sparks produced between the spark terminals 67 and 68. Ventilating openings 69 and 70 are provided in the upper part of the walls of the casing 48 to facilitate the combustion of the acetylene gas in the casing so that it may properly heat the vaporizing tube 51. As the flame produced by the acetylene gas is very hot it takes but a moment to sufficiently heat the vaporizing pipe 51, for which condition the valve 19 is opened by means of either the handle 21 or the handle 21^a, it being assumed that the controlling valve 54 is left in proper adjustment to supply the right amount of fuel to the pilot burner. Owing to the particular construction of the main vaporizer, but a short time is required to sufficiently heat it to vaporize the fuel required by the main burner, at which time the valve 9 is opened by means of either the handle 11 or the handle 11^a, and the full fire is under the boiler. An opening 71 is made in the plate 61 of the casing 48, which normally is covered by a shutter 72 to facilitate lighting the acetylene gas by a match if for any reason it is desired to do so, or if the electrical ignition system should temporarily fail to operate. This special means for igniting the starting flame is of particular value in connection with adjusting the needle valve 54 so as to avoid the necessity for continuous operation of the sparking device and to ignite the gas at only the proper time during the adjustment.

As a result of the disposition of the controlling ring 92, the switch 98 and the valve handles 11^a and 21^a at the front end of the car, a convenient means is provided for controlling the entire operation of the pilot burner so that the needle valve 54 may be properly adjusted for changing conditions, or, if desired, the needle valve 54 may be normally closed and the starting may be done entirely from the front end of the car, depending upon the conditions under which the car is operated and the pleasure of the user. Whether the pilot burner is operated from the front end of the car or from the driver's seat, it is to be borne in mind that the detent 82 retains the cock 23 in the position to which it may be actuated, owing to the mechanical connection between the two operating mechanisms.

The double lever 77 is readily removable from the operating rod 75 of the cock 23 to permit removing the gas tank 24 from the car and substituting another tank in its place, which is necessary in connection with the use of compressed gas, as is common in the art.

The cocks 95, 96 and 97 provide a convenient means for starting the pilot burner, either while the lamps 93 and 94 are in use or not, as desired.

5 While I have shown my invention in the particular embodiments herein described, I do not, however, limit myself to these particular constructions, as any equivalents may be employed without departing from the 10 spirit of my invention.

What I claim is:

1. The combination of a burner, a casing inclosing one end of the burner, a vaporizing tube contained in the casing and subject 15 only to the action of the portion of the burner contained in the casing, and a mixing tube for supplying the whole burner from the vaporizing tube, said mixing tube being inclined so as to drain outward and

closed at its inner end and supplied with 20 outlet openings only through its sides.

2. The combination of a burner, a casing inclosing one end of the burner, a vaporizing tube contained in the casing and subject only to the action of the portion of the 25 burner contained in the casing, a mixing tube for supplying the whole burner from the vaporizing tube, and a burner tube connected with the casing to deliver gas within the same to heat the vaporizing tube. 30

In witness whereof, I hereunto subscribe my name this 29th day of February, A. D., 1912.

WILLIAM H. WINSLOW.
